UNITED STATES PATENT OFFICE

CARL E. ANDERSON, OF EAST ORANGE, NEW JERSEY, ASSIGNOR TO EASTERN TOOL & MFG. CO., OF BLOOMFIELD, NEW JERSEY

SLIDE

Application filed June 12, 1931. Serial No. 543,891.

This invention relates to an improved slide preferably used on garment straps. It is used to adjust the length of the loop of the strap and is secured to one end of the strap and the strap is then threaded back through the slide.

The object of the invention is to provide a slide that is cheaply made and that is positively secured to the end of the strap. The slide requires no folding of the end of the strap and is quickly attached to the strap by pressure. The slide is well adapted for manufacture from one piece of metal and as an integral structure is sturdy and compact and lies flat against the strap.

15 The invention is illustrated in the accompanying drawing in which Figure 1 is a front view of an improved slide with the strap shown by broken lines. Figure 2 is a side view of the slide shown in Figure 1. Figure 20 3 is a vertical section of the slide of Figure 1 before it is secured to the strap. Figures 4 and 5 are sectional perspective views of modified forms of slides. Figure 6 shows another modification.

25 The slide is formed with parallel bars and end bars connecting them at the ends. In the drawing 10 is the top bar, 11 is the center bar and 12 is the bottom bar. The end bars are shown at 13 and 14. The slide is prefer- 30 ably made of a single piece of sheet metal stamped to form the frame above described and usually made concavo-convex in cross section to stiffen the top and end bars. The centre bar 11 is formed with flanges 15 at the 35 top and bottom edges to provide a positive grip on the strap 16 which is threaded through the slide as shown in Figure 2 and has its end 17 secured to the bottom bar 12.

The bottom bar 12 comprises two opposed 40 walls or jaws, the front jaw 18 having a flange 19 at its bottom edge. The jaw 20 is formed of metal bent down when the metal is punched and normally separated before attachment to the strap. This is shown in 45 Figure 3 where the space is shown as sufficient to receive the end 17 of the strap 16. The jaw 20 is curved laterally of its length and when the end of the strap is in place a suitable press is used to force the jaw 20 to flat 50 position as shown in Figure 2. This tightly

clamps the end of the strap and binds it particularly between the flange 19 and the end of the jaw 20 as at 21. The strap is then looped as at 22 and then threaded back through the slide, passing in front of centre 55 bar 11 where the flanges 15 hold it securely against slipping. The slide is adjusted by moving the slide along the strap to the desired place. No sewing of the strap is necessary with this slide; economy of fabric is 60 brought about due to the absence of folding the strap before stitching and the article is easily and quickly attached by simply placing it on the end of a strap and pressing the walls 18 and 20 against the strap.

65 I show a modification in Figure 4 in which the flanges 15 are corrugated or scalloped on the front edge as at 23. In this form the lower edge of the top bar 10 is also corrugated as at 24. The bottom bar is made up as in the 70 previously described form except that prongs 25 are punched out of the jaw 20 and are seated behind the flange 26 which is bent up to a greater extent than the flange 19 in Figure 3.

75 In Figure 5, I show a modification in which the top bar is toothed as at 27 on its bottom edge and the single flange 15 on the centre bar 11 is also toothed as at 28. In Figure 6 I show a slide in which the centre bar 11 has the upper flange 29 extended to 80 form projections 30 near each end. These projections serve to prevent a strap when under strain from being bunched at the centre or to one side.

85 Various changes can be made in the proportion and arrangement of the parts without departing from the scope of the invention which comprises a one-piece slide having within its own structure means for securing the end of a strap to the slide.

90 I claim:

95 1. A slide consisting of a single sheet of metal punched to form three parallel bars and end bars, the top bar and the end bars being concavo-convex in cross section with the concave side at the back, the center bar being U-shaped with its recessed part toward the front, the bottom bar being elliptical in cross section with its rear portion formed of material bent over from above the bottom bar 100

whereby a pair of jaws is formed for grasping and holding a strap when the jaws are squeezed together.

2. A slide consisting of a single sheet of metal punched to form three parallel bars and end bars, the top bar and the end bars being concavo-convex in cross section with the concave side at the back, the center bar being U-shaped with its recessed part toward the front, the bottom bar being elliptical in cross section with its rear portion formed of material bent over from above the bottom bar whereby a pair of jaws is formed, the folded over jaw being shorter than the front jaw of the bar, said front jaw having an upturned flange at the bottom, said jaws when flattened and forced together forming a holding means for a strap.

3. A slide consisting of a single sheet of metal punched to form three parallel bars and end bars, the top bar and the end bars being concavo-convex in cross section with the concave side at the back, the center bar being U-shaped with its recessed part toward the front, the bottom bar being elliptical in cross section with its rear portion formed of material bent over from above the bottom bar whereby a pair of jaws is formed, the folded over jaw being shorter than the front jaw of the bar, said front jaw having an upturned flange at the bottom, said jaws when flattened and forced together forming a holding means for a strap, said lower jaw having prongs struck up therefrom and disposed so as to be forced behind the flange when the jaws are forced together.

In testimony whereof he affixes his signature.

CARL E. ANDERSON.
